United States Patent Office.

C. WATERMAN, OF NEW YORK, N. Y.

Letters Patent No. 63,124, dated March 19, 1867.

IMPROVED BURGLAR ALARM.

The Schedule referred to in these Letters Patent and making part of the same.

TO ALL WHOM IT MAY CONCERN:

Be it known that I, C. WATERMAN, of the city, county, and State of New York, have invented a new and improved Burglar Alarm; and I do hereby declare that the following is a full, clear, and exact description thereof, which will enable others skilled in the art to make and use the same, reference being had to the accompanying drawings, forming part of this specification.

This invention relates to a new and improved burglar alarm for doors and windows, and it consists in a new and improved means employed for locking the bell-hammer and liberating the same, as hereinafter fully shown and described, whereby the alarm, when a door or window to which the invention is applied is partially opened, or opened sufficiently far to operate the alarm, cannot be stopped by suddenly closing the door or window. Hence, a burglar, in opening a door or window, and causing the alarm to be sounded thereby, cannot stop it by closing the door or window; and the inmates of a house, therefore, will be sure to hear the alarm. In the accompanying sheet of drawings—

Figure 1 is a view of the inner side of a door having my invention applied to it.

Figure 2, a detached view of the shell which contains the hammer-operating mechanism.

Similar letters of reference indicate corresponding parts.

A represents a cylindrical case, which may be of sheet metal, or other suitable material, and which contains the mechanism of an ordinary bell alarm, the rod B of the bell-hammer extending through a slot, a, in the case, and the latter having a hook, C, attached, or other device for holding or locking the end of the rod B when it is not designed to have the alarm operate. D is the bell, against which the hammer E of the rod B acts. The case A and bell D are secured to the door-frame just above the door A^X; and to the latter there is attached an arm, F, which has a rod, G, pivoted in its outer end, said rod being allowed to work or rise and fall freely to a certain extent. This rod G, when the door is closed, rests upon the hammer-rod B, and renders it inoperative by holding it down upon the bell; but when the door is opened the rod G of course is moved off from the rod B, and the latter is allowed to operate, and the alarm consequently sounded. When the rod G is moved off from the hammer-rod B, the former drops, by its own gravity, out of line with the hammer, and so that, in closing the door, the rod G will not come in contact with B, and the alarm therefore cannot be stopped. If it could be stopped by the closing of the door, the alarm would be sounded for such a short period that the inmates of a house would, in many instances, fail to hear it. By my improvement, therefore, the only way in which the alarm can be stopped is by obtaining a chair or step-ladder and adjusting the catch or fastening C; and this would occupy some time, and be too much trouble to be practised by burglars. The hook or fastening C is necessary, as it holds the hammer-rod B, and renders the alarm inoperative when not required, and admits of the hammer-operating mechanism being always kept wound up ready for use at any moment.

I claim as new, and desire to secure by Letters Patent—

1. The rod G, connected by a pivot, or any suitable joint, to the arm F on the door A^X, and arranged in relation with the hammer-rod B of an ordinary bell alarm, to operate in the manner substantially as and for the purpose set forth.

2. The hook or fastening C, in combination with the hammer-rod B, and the other rod G, substantially as and for the purpose specified.

The above specification of my invention signed by me this sixth day of February, 1867.

C. WATERMAN.
